UNITED STATES PATENT OFFICE.

HORATIO G. GILLMOR, OF WASHINGTON, DISTRICT OF COLUMBIA.

RAIL-ANCHOR.

1,254,134.

Specification of Letters Patent. Patented Jan. 22, 1918.

Application filed June 12, 1916. Serial No. 103,298.

To all whom it may concern:

Be it known that I, HORATIO G. GILLMOR, a citizen of the United States, residing at Washington, in the District of Columbia, have invented a new and useful Improvement in Rail-Anchors, of which the following is a specification accompanied by drawings.

This invention relates to rail anchors, 10 anticreepers, or devices for preventing the creeping of the rails of railways, and one of its objects is to form a simple device which may be attached to or used in connection with the tie plate and which will be 15 efficient in preventing the creeping action.

Another object is to provide a device which shall be efficient in resisting the tendency of the rail to move in either direction.

The invention is illustrated in a preferred 20 embodiment in the accompanying drawing, in which—

Figure 1 is an end view showing the rail in section.

Fig. 2 is a plan view of the device in position upon the rail.

Fig. 3 is a sectional view showing the parts in one of the positions assumed during the placing of the device upon the rail.

Similar letters refer to similar parts 30 throughout the several views.

In the embodiment of the invention illustrated in the drawings, A represents the rail having a head portion B and a base portion C, which rests upon the tie plate D. 35 The tie plate D in turn is supported by the tie E, a portion of one of which is shown in the drawings, and is secured thereto by the spikes or screws F.

The spring G is preferably formed from 40 a sheet or plate and has a portion I, which is provided with two arms or flanges K, and is arranged to be forced into an aperture L in the tie plate D between the edge of the rail base C and the tie plate D so 45 that the corners M will bite into the rail edge. The arms or flanges K are tapered at N to facilitate entering and forcing the portion I of the spring G between the rail and the tie plate D. The spring G also has 50 two arms or flanges O; which, when the spring is in the operative position, have corners P engaging the upper surface of the rail base C. At the upper end of the spring G there are surfaces Q which en-

gage the under side of the head of the rail. 55 The portion I of the spring G is connected to the body of the spring by the relatively flat portion R. The tie plate D may have a rib S arranged to engage one edge of the rail base and the aperture L may be provided with special stiffening T to increase the bearing of the portion I of the spring G with the tie plate D.

The device is placed in position by entering the portion I of the spring G in the aperture L of the tie plate D, which has already been placed upon the tie and secured thereto by the spikes or screws F; and driving or otherwise forcing it down so that the arms or flanges K are forced in between the rail 70 edge and the tie plate with the corners M biting into the edge of the rail base until the lower edges of the arms or flanges O bear upon the upper corner of the rail base C as illustrated in Fig. 3. This forces the 75 rail base edge opposite the portion I of the spring into contact with the rib S of the tie plate D or with the spikes F if there be no rib and causes the rail edge to be gripped by the biting corners M of the arms K of 80 the portion I. When the device is in this position the surfaces Q of the upper end of the spring G will be about to engage with the under side of the head B of the rail and

by forcing the upper portion of the spring 85 G transverse to the rail, either by driving it with a hammer or by the use of a suitable wrench the spring G may be forced to the final operative position shown in Figs. 1 and 2. While being so forced transversely 90 of the rail the portion R of the spring G acts as a flat spring and the arms O also form with the body of the spring G a spring and as the arms O contact with the upper surface of the rail base C the portion of the 95 spring G formed by that part of the body and the arms O tends to flatten somewhat with the corner P of the arms O in contact with the upper surface of the rail base; and in the final operative position of the parts, 100 shown in Figs. 1 and 2, the spring G is pressing the surfaces Q upwardly against the under side of the rail head B by the combined spring action of the flat spring portion R and the spring action of the portion 105 carrying the arms O and, at the same time, the spring G is pressing downwardly upon the upper surface of the rail base C and

pressing the biting corners P of the arms O into the rail base C by the spring action of these arms.

It will thus readily be seen that the spring 5 G is firmly gripping the rail edge with the arms K of the portion I and at the same time gripping the upper surface of the base C and the under side of the head B and that the spring G, intending to resume the form 10 from which it has been sprung, locks the parts in position, the rail head B preventing any upward movement of the spring G and the engagement of the portion I with the tie plate preventing any lateral movement 15 of the spring G.

It will also be readily seen and understood that if the grip of the device upon the rail is not sufficient when the parts have been placed in their operative position to 20 withstand the forces tending to move the rail or cause it to creep, very slight movement of the rail in relation to the tie plate will cause deflection of one or the other of the arms K (depending upon the direction 25 in which the rail tends to move) and also of the arms O and that this will increase the biting effect of the biting corners M and P upon the edge and upper surface of the rail base C and thus automatically increase 30 the resistance of the device to further movement of the rail.

It will also be seen that the device will be efficient in preventing movement of the rail in either direction.

35 While I have described the invention as embodied in a preferred construction, modifications might be made without departing from the principles of the invention. Therefore, I do not wish to be understood as limiting 40 the invention to the particular construction, arrangement and devices shown and described, except so far as these limitations are specifically set forth in the claims herein.

I claim and desire to secure by Letters 45 Patent:—

1. As a new article of manufacture, a spring for use with a tie plate for the preventing of the creeping of rails having divergent arms shaped to engage the rail base 50 and a portion adapted to be forced in between the head and base flange of the rail and lock the spring in position.

2. As a new article of manufacture a spring, adapted to engage the edge of a rail 55 base and a tie plate to resist tendency of the rail to creep and to engage and exert upward pressure upon the rail head in tending to resume a form from which it was sprung.

3. As a new article of manufacture, an attachment to a tie plate comprising a spring arranged to engage said tie plate and the edge and upper surface of the rail base and the under side of the head of the rail to prevent creeping movement of the rail.

65 4. A rail anchor comprising an abutment

at one side of the rail and a spring on the other side of the rail which engages the edge and upper surface of the base flange of the rail and the under side of the head of the rail and prevents creeping thereof.

5. An anticreeper comprising an abutment 70 at one side of the rail and a spring at the other side of the rail with a biting edge which engages the rail base and prevents creeping and an upward extension which 75 engages the under side of the head of the rail and locks said spring in position.

6. A rail stay comprising a tie plate and a spring, engaging said tie plate, having an arm bearing at an inclination against the 80 edge of the rail base to prevent creeping and a portion engaging the under side of the head of the rail for retaining said spring in position.

7. A device for preventing the creeping of 85 rails including, in combination with the rail and a tie plate, a member engaging the under side of the head of the rail and the tie plate and having yielding engagement with the upper surface of the rail base.

8. A rail anchor including, in combination with the rail and a tie plate, a member engaging the head and the vertical edge of the base of the rail and the tie plate at one side of the rail and having yielding engagement 95 with the upper surface of the base flange of the rail.

9. An anticreeper comprising a tie plate and a part adapted to engage the tie plate and the vertical edge of the rail base flange 100 and to be forced in between the under side of the head and the upper side of the base flange at one side of the rail.

10. A device for preventing the creeping of rails comprising a transverse member provided with means for engaging the rail base at one side of the rail and a spring engaging the said transverse member the head of the rail and the edge of the base flange of the rail at the other side of the rail.

11. A rail anchor comprising a transverse member having means for engaging the rail base at one side of the rail and a spring engaging said transverse member, the head and the base flange of the rail at the other 115 side of the rail and exerting pressure upon the rail and said transverse member in seeking to resume a position from which it was sprung.

12. An anticreeper, including a tie plate 120 and a member engaging the under side of the head of the rail and said tie plate and having yielding engagement with the upper side of the rail base.

13. A rail anchor, including a spring arranged to fit in between the head and base flange of the rail and to engage a tie plate at one side of the rail and to press down upon the rail base and up against the under side of the rail head.

14. A device for preventing the creeping of rails comprising a part arranged to be applied to the rail between the head and base flange and engage a tie plate at one side of the rail held in gripping engagement with the rail by the spring action of said part upon the rail base. 5
15. A rail anchor comprising a member designed to be held between the rail head and base flange and to have yielding engagement therewith, having a portion projecting below the rail base at one side of the rail and a holding plate formed with an opening receiving said projecting portion. 10
16. An anticreeping device comprising a part adapted to be applied to the rail between the head and base thereof having a spring portion engaging the upper surface of the rail base and forcing said part up 20 against the rail head and a portion extending below the rail and a holding plate formed with an aperture receiving said projection so as to prevent both transverse and longitudinal movement of said part. 25
17. A device for preventing the creeping
- of rails comprising a holding plate and a spring forced in between said holding plate and the edge of the rail base and between the head and base flange of the rail. 30
18. A rail anchor comprising a spring engaging the under side of the head and the vertical edge of the base flange at one side of the rail and a tie plate so engaging said spring as to hold said spring in position and prevent the creeping of the rail. 35
19. A rail anchor, provided with means for giving it a fixed position with respect to the roadbed and with rail clamping means, comprising a spring formed from a plate and constructed to be driven in between the head and the base flange of the rail. 40
20. A rail anchor provided with means for giving it a stationary position with respect to the roadbed and with rail clamping means comprising coengaging members having a pivoting relation with each other, one of which is a spring plate engaging the rail head and the upper surface of the rail base flange. 45
